US00D947208S

(12) **United States Design Patent** (10) **Patent No.:** **US D947,208 S**
(45) **Date of Patent:** **** Mar. 29, 2022**

(54) **DISPLAY SCREEN OR PORTION THEREOF
WITH GRAPHICAL USER INTERFACE**

(71) Applicant: **ABB Schweiz AG**, Baden (CH)

(72) Inventors: **Marko Kiikkala**, Laihia (FI); **Olli Rintamäki**, Vähäkyrö (FI); **Tarmo Korhonen**, Parola (FI); **Käre Särs**, Töölby (FI)

(73) Assignee: **ABB Schweiz AG**, Baden (CH)

(**) Term: **15 Years**

(21) Appl. No.: **29/667,115**

(22) Filed: **Oct. 18, 2018**

(30) **Foreign Application Priority Data**

Apr. 19, 2018 (EM) 005240470

(51) **LOC (13) Cl.** **14-04**

(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface; and,

FIG. 2 is a second embodiment thereof.

The broken lines showing a display screen or portion thereof and elements of the graphical user interface illustrate portions of the article, and form no part of the claimed design.

**1 Claim, 2 Drawing Sheets
(2 of 2 Drawing Sheet(s) Filed in Color)**
